[57] CLAIM

The original design for an infrared rays sensor, as shown and described.

DESCRIPTION

FIG. 1 is a perspective view of an infrared rays sensor showing our new design;

FIG. 2 is a top plan view thereof;

FIG. 3 is a front elevational view thereof;

FIG. 4 is a bottom plan view thereof;

FIG. 5 is a right side elevational view thereof; (of which a left side elevational view would be a mirror image);

FIG. 6 is a rear elevational view thereof; and,

FIG. 7 is a sectional view taken along line 7—7 of FIG. 3.
